Filed June 10, 1969, Ser. No. 17,625

Term of patent 3½ years

Int. Cl. D6—01

U.S. Cl. D15—11

FIG. 1 is a front perspective view of a corner sofa and table combination showing my new design;

FIG. 2 is a left side elevational view of the corner sofa and table combination shown in FIG. 1 on a reduced scale; and

FIG. 3 is a right side elevational view of the corner sofa and table combination shown in FIG. 1 and on the same scale as FIG. 2.

The back of the corner sofa and table combination shown is substantially plain and unornamented.

I claim:

The ornamental design for the corner sofa and table combination or the like, substantially as shown and described.
